UNITED STATES PATENT OFFICE.

DAVID F. VAUGHAN, OF RIVERTON, NEW JERSEY.

ANTICREEPER FOR RAILROAD-RAILS.

1,216,256.

Specification of Letters Patent. Patented Feb. 13, 1917.

Application filed September 21, 1916. Serial No. 121,345.

To all whom it may concern:

Be it known that I, DAVID F. VAUGHAN, a citizen of the United States, residing at Riverton, in the county of Burlington and State of New Jersey, have invented certain new and useful Improvements in Anticreepers for Railroad-Rails, of which the following is a specification.

My invention relates to improvements in anticreepers for railroad rails, and the object of my invention is to provide a novel, inexpensive, strong and durable anticreeper which may be readily applied to and removed from a rail and which when in service will effectually prevent the creeping of the rail under varying weather and traffic conditions.

With this object in view, my invented anticreeper consists of the elements and the combinations of them hereinafter described and claimed.

In the accompanying drawings, illustrating my invention:

Fig. 1 is an end view of a tie forming a stationary part of a road bed, a railroad rail thereon and my improved anticreeper applied to the rail.

Fig. 2 is a plan view of the parts shown in Fig. 1.

Fig. 3 is a vertical section on line 3—3 of Fig. 1.

Fig. 4 is a side view of a portion of a rail with the rail engaging element of the anticreeper applied thereto and in its normal condition.

Fig. 5 is a vertical section on line 5—5 of Fig. 4, including the locking member in proper position to be driven into locking position.

Fig. 6 is a plan view of the parts shown in Figs. 4 and 5.

Fig. 7 is a detail showing the prevention of the insertion of the locking member in a wrong position.

Fig. 8 is a view of the sheet metal blank from which the rail engaging element of the anticreeper is formed.

Referring to the drawings, 2 designates a railroad rail and 4 a cross-tie which forms a part of the road bed and supports the rail 2 in the usual manner. The rail 2 comprises, as usual, a base 6 resting on the cross-tie 4, a central web 7 rising from the base 6, and a head 8 supported on the web 7.

My improved anticreeper is applied to

the rail 2 and comprises a rail engaging member 9 and a locking member 10.

The rail engaging member 9, in the present instance, is formed of sheet metal from the blank shown in Fig. 8, and it comprises a bar 11 adapted to extend transversely beneath the rail 2 and having a tie engaging projection or abutment 12, and having rail engaging parts on the ends thereof adapted to engage the respective sides of the rail base. One end of the bar 11 is bent upwardly and inwardly and forms a jaw 13 adapted to receive and grip one side of the rail base 6; and the other end of the bar 11 is bent to form an upwardly extending arm 14 adapted to engage the other side of the rail base 6. The projection or abutment 12 is adapted to engage the cross-tie 4 or other stationary part of the road bed to prevent the rail from creeping.

The end portion of the bar 11 carrying the arm 14 is inclined downwardly from the end portion of the bar carrying the jaw 13, so that, in the normal condition of the bar 11 with its jaw end 13 embracing one side of the rail base 6 and engaged with the top and bottom thereof, the other end of the bar carrying the arm 14 will be inclined downwardly and spaced from the bottom of the rail base 6, as shown in Figs. 4 and 5, whereby when the downwardly inclined end portion of the bar 11 is raised toward the bottom of the rail base 6, the bar 11 will be placed under tension.

The end of the bar 11 carrying the arm 14 is preferably caused to incline downwardly by producing a twist in the bar, so that in the normal condition of the bar with its jaw 13 engaged with one side of the rail base 6, but one side of the end portion carrying the arm 14 will be inclined downwardly, as clearly shown in Figs. 4 and 5.

The arm 14 has an opening 15 extending therethrough transversely to the rail 2. The top and bottom walls of this opening 15 are substantially parallel to the rail base 6 when the twisted or inclined end of the bar 11 is raised to the position shown in Figs. 1, 2 and 3, and the top and bottom walls of the opening 15 are inclined with relation to the rail base 6 when the bar 11 is in its normal condition, as clearly shown in Figs. 4, 5 and 6.

The opening 15 receives the locking member 10 which has sides 17 and 18 substantially parallel to the end walls of the opening 15, and which has upper and lower faces 19 and 20, respectively, which converge and form a wedge. One corner of this wedge shaped member 10, at the small end thereof, is cut away obliquely to its sides 17 and 18, forming a beveled portion 21, as shown, and the top of the member 10 has a small shoulder 22 formed thereon and extending between the sides 17 and 18 thereof.

In applying the anticreeper to the rail, the bar 11 is first placed beneath the rail base 6 with the jaw 13 engaged with one side of the rail base, as shown in Figs. 4, 5 and 6. In this position of the bar 11, the arm 14 and its opening 15 are inclined, and only a portion of the opening 15 extends above the top of the outer edge of the adjacent side of the rail base 6, as shown in Fig. 4. After the bar 11 has been placed in this position, the small end of the wedge member 10 is placed within the opening 15 and a slight distance over the adjacent side of the rail base 6 with the shoulder 22 up and with the beveled portion of the member 10 toward the lower end of the arm 14. This is the proper and the only manner in which the member 10 can be placed within the opening 15 and over the adjacent edge of the rail base without springing upwardly the downwardly inclined end of the bar 11. If the person applying the anticreeper should attempt to enter the wedge member 10 into the opening 15 and over the edge of the rail base 6 with the shoulder 22 down and with the beveled portion 21 toward the upper end of the arm 14, the beveled portion 21 would engage the outer portion of the upper end wall of the opening 15 and force the opposite side 18 of the member 10 downwardly to a position too low to pass over the adjacent edge of the rail base 6 and thus prevent the wrong insertion of the locking member 10 as shown in Fig. 7. After the locking member 10 has been placed within the opening 15 and over the side of the rail base 6, as shown in Figs. 5 and 6, the member 10 is driven on inwardly by a hammer or other suitable tool to the position shown in Figs. 1, 2 and 3. As the member 10 is thus driven to the position shown in Figs. 1, 2 and 3, it forces the downwardly inclined portion of the bar 11 up toward the bottom of the rail base 6 and places the bar 11 under tension, causing the jaw 13, bar 11 and member 10 to firmly grip the rail and lock the rail and the anticreeper together.

Just as the member 10 reaches the position shown in Figs. 1, 2 and 3, while being driven into place, the shoulder 22 escapes the inner face of the arm 14, which then springs back to the base of the shoulder 22 and rests upon the outer end of the member 10 and the

shoulder 22 thus prevents the accidental withdrawal of the locking member 10 from the arm 14.

When it is desired to remove the anticreeper from the rail, the locking member 10 is driven farther in toward the center of the rail until the outer end of the member escapes the inner face of the arm 14, thereby first raising the arm 14 slightly and then freeing it and permitting the bar 11 to spring back to normal condition, whereupon the parts may be removed from the rail.

The bar 11, jaw 13 and arm 14 are preferably so formed that when the anticreeper is applied to the rail, the bar 11 will extend obliquely beneath the rail from side to side of the base 6 thereof and the jaw 13 and arm 14 will extend parallel to the sides of the rail base, thereby bringing the forward end of the arm 14 back near a position directly opposite to the rearward end of the jaw 13; and the tie abutment 12 preferably projects from the bar 11 at or near the end thereof carrying the jaw 13. By this construction, any creeping action of the rail 2 will carry the end of the bar 11 having the arm 14 forwardly while the abutment 12 engaging the cross tie 4 will prevent forward movement of the end of the bar having the jaw 13, thereby causing the forward end of the arm 14 and the rearward end of the jaw 13 to bind against the edges of the rail base 6 and thus cause the anticreeper to increase its grip upon the rail under the influence of the rail as it tends to creep.

I claim:

1. An anticreeper for railroad rails comprising a spring bar adapted to extend beneath a rail base and having a jaw on one end thereof adapted to engage one side of a rail base and an upwardly extending arm on the other end thereof adapted to engage the other side of said rail base, said bar in its normal condition having its end portion provided with the arm inclined downwardly in spaced relation to the rail base and adapted to be sprung upwardly toward the same when its jaw is engaged with one side of the rail base, and a locking member adapted to be inserted between a part of said arm and the top of the adjacent side of the rail base and to thereby hold the inclined portion of the bar in an upwardly sprung position.

2. An anticreeper for railroad rails comprising a spring bar adapted to extend beneath a rail base and having a jaw on one end thereof and an upwardly extending arm on the other end thereof and having a tie abutment formed thereon, said bar in its normal condition having its end portion provided with the arm inclined downwardly in spaced relation to the rail base and adapt-

ed to be sprung upwardly toward the same when its jaw is engaged with one side of the rail base, and a locking member adapted to be inserted between a part of said arm and 5 the top of the adjacent side of the rail base and to thereby hold the inclined portion of the bar in an upwardly sprung position.

3. An anticreeper for railroad rails comprising a bar adapted to extend beneath a 10 rail base and having a jaw on one end thereof and an upwardly extending arm on the other end thereof, said bar in its normal condition having a twist formed therein causing one side of the end portion provided with the arm to be inclined downwardly in spaced relation to the rail base when its jaw is engaged with one side thereof, and a locking member adapted to be inserted between a part of said arm and the 15 top of the adjacent side of the rail base and to thereby draw said inclined end portion up toward the rail base and place the bar under tension.

4. An anticreeper for railroad rails comprising a bar adapted to extend beneath a 20 rail base and having a jaw on one end thereof and an upwardly extending arm on the other end thereof, said bar in its normal condition having a twist formed therein causing one side of the end portion provided with the arm to be inclined downwardly in spaced relation to the rail base when its jaw is engaged with one side thereof, and a wedge shaped locking member adapted to be inserted between a part of 25 said arm and the top of the adjacent side of the rail base and to thereby draw said inclined end portion up toward the rail base and place the bar under tension.

40 5. An anticreeper for railroad rails comprising a bar adapted to extend beneath a rail base and having a jaw on one end thereof and an upwardly extending arm on the other end thereof, said bar in its normal condition having its end portion provided with the arm inclined downwardly in spaced relation to the rail base when its jaw is engaged with one side thereof, and said arm being provided with an opening having an 45 upper wall which is inclined downwardly and longitudinally with respect to the adjacent side of the rail base, and a locking member adapted to be inserted between said wall and the top of the adjacent side of the rail base and to thereby draw said inclined end portion up toward the rail base and place the bar under tension, said member having a beveled portion adapted to coöperate with said 50 arm and the rail base and permit only the proper insertion of said member.

60 6. An anticreeper for railroad rails comprising a bar adapted to extend beneath a rail base and having a jaw on one end thereof and an upwardly extending arm on the

other end thereof, said bar in its normal condition having its end portion provided with the arm inclined downwardly in spaced relation to the rail base when its jaw is engaged with one side thereof, and said arm being provided with an opening having an upper wall which is inclined downwardly and longitudinally with respect to the adjacent side of the rail base, and a locking member having its upper and lower faces converging to form a wedge adapted to be inserted between said wall and the top of the adjacent side of the rail base and to thereby draw said inclined end portion up toward the rail base and place the bar under tension, said member having a beveled portion connecting its upper and lower faces and being adapted to coöperate with said arm and the rail base and permit only the proper insertion of said member.

65 7. An anticreeper for railroad rails comprising a bar adapted to extend beneath a rail base and having a jaw on one end thereof and an upwardly extending arm on the other end thereof, said bar in its normal condition having a twist formed therein causing one side of the end portion provided with the arm to be inclined downwardly in spaced relation to the rail base when its jaw is engaged with one side thereof, and said arm being provided with an opening having an upper wall which is inclined downwardly and longitudinally with respect to the adjacent side of the rail base, and a locking member adapted to be inserted between said wall and the top of the adjacent side of the rail base and to thereby draw said inclined end portion up toward the rail base and place the bar under tension, said member having a beveled portion adapted to coöperate with said arm and the rail base and permit only the proper insertion of said member.

80 8. An anticreeper for railroad rails comprising a bar adapted to extend beneath a rail base and having a jaw on one end thereof and an upwardly extending arm on the other end thereof, said bar in its normal condition having a twist formed therein causing one side of the end portion provided with the arm to be inclined downwardly in spaced relation to the rail base when its jaw is engaged with one side thereof, and said arm being provided with an opening having an upper wall which is inclined downwardly and longitudinally with respect to the adjacent side of the rail base, and a locking member having its upper and lower faces converging to form a wedge adapted to be inserted between said wall and the top of the adjacent side of the rail base and to thereby draw said inclined end portion up toward the rail base and place the bar under tension, said member having a beveled portion connecting its upper and lower faces and being adapted to coöperate with said arm and the rail base.

and permit only the proper insertion of said member.

9. An anticreeper for railroad rails comprising a bar adapted to extend beneath a rail base and having a jaw on one end thereof and an upwardly extending arm on the other end thereof, said bar in its normal condition having its end portion provided with the arm inclined downwardly in spaced relation to the rail base when its jaw is engaged with one side thereof, and said arm having an opening extending therethrough transversely of the rail, and a locking member adapted to be inserted into said opening and to engage the top wall thereof and the adjacent side of the rail base and to thereby draw said inclined end portion up toward the rail base and place the bar under tension.

10. An anticreeper for railroad rails comprising a bar adapted to extend beneath a rail base and having a jaw on one end thereof and an upwardly extending arm on the other end thereof, said bar in its normal condition having a twist formed therein causing one side of the end portion provided with the arm to be inclined downwardly in spaced relation to the rail base when its jaw is engaged with one side thereof, and said arm having an opening extending therethrough transversely of the rail, and a locking member adapted to be inserted into said opening and to engage the top wall thereof and the adjacent side of the rail base and to thereby draw said inclined end portion up toward the rail base and place the bar under tension.

11. An anticreeper for railroad rails comprising a bar adapted to extend beneath a rail base and having a jaw on one end thereof and an upwardly extending arm on the other end thereof, said bar in its normal condition having its end portion provided with the arm inclined downwardly in spaced relation to the rail base when its jaw is engaged with one side thereof, and a locking member adapted to be inserted between a part of said arm and the top of the adjacent side of the rail base and to thereby draw said inclined end portion up toward the rail base and place the bar under tension, said member having a shoulder formed thereon adapted to engage a part of said arm and prevent reverse movement of said member after the insertion thereof.

12. An anticreeper for railroad rails comprising a bar adapted to extend beneath a rail base and having a jaw on one end thereof and an upwardly extending arm on the other end thereof, said bar in its normal condition having its end portion provided with the arm inclined downwardly in spaced relation to the rail base when its jaw is engaged with one side thereof, and a wedge shaped locking member adapted to be inserted between a part of said arm and the top of the adjacent side of the rail base and to thereby

draw said inclined end portion up toward the rail base and place the bar under tension, said member having a shoulder formed thereon adapted to engage a part of said arm and prevent reverse movement of said member after the insertion thereof.

13. An anticreeper for railroad rails comprising a bar adapted to extend beneath a rail base and having a jaw on one end thereof and an upwardly extending arm on the other end thereof, said bar in its normal condition having its end portion provided with the arm inclined downwardly in spaced relation to the rail base when its jaw is engaged with one side thereof, and said arm being provided with an opening having an upper wall which is inclined downwardly and longitudinally with respect to the adjacent side of the rail base, and a locking member having its upper and lower faces converging to form a wedge adapted to be inserted between said wall and the top of the adjacent side of the rail base and to thereby draw said inclined end portion up toward the rail base and place the bar under tension, said member having a beveled portion connecting its upper and lower faces and being adapted to coöperate with said arm and the rail base and permit only the proper insertion of said member, and said member having a shoulder formed thereon adapted to engage a part of said arm and prevent reverse movement of said member after the insertion thereof.

14. An anticreeper for railroad rails comprising a bar adapted to extend beneath a rail base and having a jaw on one end thereof and an upwardly extending arm on the other end thereof, said bar in its normal condition having a twist formed therein causing one side of the end portion provided with the arm to be inclined downwardly in spaced relation to the rail base when its jaw is engaged with one side thereof, and said arm being provided with an opening having an upper wall which is inclined downwardly and longitudinally with respect to the adjacent side of the rail base, and a locking member having its upper and lower faces converging to form a wedge adapted to be inserted between said wall and the top of the adjacent side of the rail base and to thereby draw said inclined end portion up toward the rail base and place the bar under tension, said member having a shoulder formed thereon adapted to engage a part of said arm and prevent reverse movement of said member after the insertion thereof.

15. An anticreeper for railroad rails comprising a spring bar adapted to extend be-

neath a rail base and having a jaw on one end thereof adapted to engage one side of a rail base and an upwardly extending arm on the other end thereof adapted to engage 5 the other side of a rail base, said arm having an opening therein adapted to receive a locking member, said bar in its normal condition having its end portion provided with the arm inclined downwardly in spaced relation to the rail base and adapted to be sprung upwardly toward the same when its jaw is engaged with one side of the rail 10 base, and a locking member adapted to be

inserted into said opening and to engage the adjacent side of the rail base to thereby 15 draw said inclined portion up toward the rail base and place the bar under tension, said opening extending above the plane of the upper face of the adjacent side of the rail base when said bar is in normal condition with its jaw engaged with one side of a rail base. 20

In testimony whereof I affix my signature hereto.

DAVID F. VAUGHAN.
